TEXTILE CRIMPING DEVICE

James P. Richeson, Decatur, Ala., assignor to Monsanto Company, a corporation of Delaware
Filed Apr. 30, 1963, Ser. No. 276,821
4 Claims. (Cl. 28—1)

This invention relates to textile crimping devices and more particularly to devices for maintaining alignment of drive shafts in a tow crimper.

In one type of machine for crimping a bundle of chemical textile filaments a pair of rolls are used for forcing the bundle of filaments, or tow, into a crimping chamber. These rolls are mounted on parallel shafts, one of which is movable so that the rolls can be urged together with great force. Because the rolls are on or near the ends of the shafts, the shafts tend to spring apart when the loading force is applied. This prevents the rolls from moving completely face-to-face, thereby resulting in a greater pressure being applied to one side of the tow than to the other. Since the rolls must be accessible for inspection, cleaning and replacement of the rolls, it has not been feasible to mount bearings on the outer ends of the drive shafts to prevent roll separation. With this in mind, one of the objects of this invention is to provide a novel and improved shaft supporting device.

Another object of this invention is to provide a quick-detachable support for holding a pair of drive shafts in alignment.

A further object of this invention is to provide a clamp for holding a pair of parallel drive shafts to prevent movement of the shafts away from each other.

One embodiment of the present invention contemplates, in a tow crimper having crimping rolls mounted on parallel drive shafts, a clamp having a fixed arm or jaw and a movable arm or jaw. The fixed jaw engages a bearing on one of the shafts, while the movable jaw engages a bearing on the other shaft. A heavy fluid cylinder is used to urge the movable jaw toward the fixed jaw to prevent movement of the shafts away from each other.

Other objects and advantages of the invention will become apparent when the following detailed description is read in conjunction with the appended drawing, in which

FIGURE 1 is a front view of the device showing the positioning of the device on a pair of shafts, and

FIGURE 2 is a top view showing the position of the clamp relative to the crimping rolls.

Referring now in detail to the drawing, a pair of drive shafts 11 and 12 are shown supporting a pair of crimping rolls 13 and 14. A mechanism (not shown) of a well known type is used to urge the shafts toward each other to force the rolls 13 and 14 together. Bearings 15 and 16 support the rolls 13 and 14 at points behind these rolls. A guide 17 directs a tow 18 into the nip of the rolls 13 and 14, these rolls forcing the tow into a crimping chamber 19. This structure is conventional.

To prevent separation of the front ends of the shafts 11 and 12 under load, a supporting device 20 is used. This device includes a bracket 23 to which is secured a fixed arm or jaw 24. The fixed jaw 24 is provided with an arcuate recess 25 for receiving the outer race of a bearing 28 mounted on the shaft 12.

At the other end of the bracket 23 there is pivotally attached a movable arm or jaw 29 having an arcuate recess 30 for receiving the outer race of a bearing 32 mounted on the shaft 11. The arcuate recesses 25 and 30 face each other to hold the bearings 28 and 32 therebetween.

A heavy fluid cylinder 33 secured to the end of the bracket 23 is provided with a piston rod 35 which engages the movable jaw 29 to urge this jaw toward the fixed jaw 24. A fluid supply 37 is connected through a pressure

2

regulating valve or device 38 to the cylinder 33. By adjusting the pressure of the fluid applied to the cylinder 33 the force applied to hold the shafts 11 and 12 against movement away from each other can be adjusted. This force should be sufficiently great to hold the roll faces parallel to each other at the nip when a tow is passing between the rolls.

In operation, the fluid cylinder applies a force to the movable jaw 29 to prevent movement of the shafts 11 and 21 away from each other. When it is desired to inspect, clean or replace the crimping rolls 13 and 14, the fluid pressure is lowered sufficiently to allow manual movement of the movable arm or jaw 29 away from and clear of the bearing 32. The complete device 20 is then lifted off the shafts and set aside. After cleaning, etc., the device 20 is replaced on the shafts 11 and 12 and pressure again applied to the cylinder 33. It can be readily seen that removal or replacement of the device can be effected almost in seconds.

It is to be understood that the embodiment disclosed herein is merely illustrative and that numerous other embodiments can be contemplated without departing from the spirit and scope of the invention.

What is claimed is:

1. In a tow crimping apparatus having a pair of crimping rolls mounted on parallel drive shafts, a shaft supporting device comprising a bracket, a first arm secured to one end of the bracket and adapted to support one of said shafts, a second arm movably connected to the bracket for supporting the other shaft, said arms being positioned in facing relationship with the shafts therebetween, and means engaging the movable arm for urging said movable arm toward said fixed arm to prevent movement of the shafts away from each other when a bundle of filaments is passed between the rolls.

2. In a tow crimping apparatus having a pair of crimping rolls mounted on parallel drive shafts, a device for preventing movement of the shafts away from each other comprising a pair of bearings mounted on the shafts in front of the rolls, a bracket extending across the shafts above said bearings, a first arm secured to one end of the bracket and having an arcuate recess for receiving the outer race of the bearing on one of said shafts, a second arm movably mounted on the bracket and having an arcuate recess for receiving the outer race of the other bearing, said arms being positioned in facing relationship with the shafts therebetween, and means secured to the bracket for engaging and urging the movable arm toward the fixed arm to prevent movement of the shafts away from each other when a tow is passed between the rolls.

3. In a tow crimping apparatus having a pair of crimping rolls mounted on parallel drive shafts, a device for preventing movement of the shafts away from each other, comprising a pair of bearings mounted on the shafts in front of the rolls, a bracket positioned above and extending across the shafts, a first arm secured to the bracket and having an arcuate recess for receiving the outer race of one of the bearings, a second arm pivotally secured to the bracket and having an arcuate recess for receiving the outer race of the other bearing, said arms being positioned in facing relationship with the bearings therebetween, and a fluid cylinder secured to the bracket and having a piston rod engaging the second arm for urging said second arm toward said first arm to prevent movement of the shafts away from each other when a tow is passed between the rolls.

4. In a tow crimping apparatus having a pair of crimping rolls mounted on parallel drive shafts, a device for preventing movement of the shafts away from each other, comprising a pair of bearings mounted on the shafts in front of the rolls, a bracket positioned above and ex-

tending across the shafts, a first arm secured to the bracket and having an arcuate recess for receiving the outer race of one of the bearings, a second arm pivotally secured to the bracket and having an arcuate recess for receiving the outer race of the other bearing, said arms being positioned in facing relationship with the bearings therebetween, and a fluid cylinder secured to the bracket and having a piston rod engaging the second arm for urging said second arm toward said first arm to prevent movement of the shafts away from each other when a tow is passed between the rolls, a pressure regulating device, and a source of fluid under pressure, said fluid source being connected through the regulating device to the cylinder.
